UNITED STATES PATENT OFFICE

156,606

DUAL PARKING METER

Harry E. Conrad, Los Angeles, Calif., assignor of
one-fourth to Louis F. Green and Allan L.
Alfsen, both of Los Angeles, Calif.

Application November 24, 1948, Serial No. 149,812

Term of patent 14 years

(Cl. D52—3)

To all whom it may concern:

Be it known that I, Harry E. Conrad, a citizen of the United States of America, residing at Los Angeles, in the county of Los Angeles and State of California, have invented a new, original, and ornamental Design for a Dual Parking Meter, of which the following is a specification, reference being had to the accompanying drawing, forming part thereof.

Figure 1 is a front elevational view;

Figure 2 is a side elevational view; and

Figure 3 is a rear elevational view of a dual parking meter, showing my new design.

I claim:

The ornamental design for a dual parking meter, as shown.

HARRY E. CONRAD.
